CLAIM

We claim the ornamental design for a beam projector, as shown and described.

DESCRIPTION

FIG. 1 is a top front perspective view of a beam projector showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and

FIG. 8 is an enlarged view of the encircled portion 8 in FIG. 1;

FIG. 9 is an enlarged view of the encircled portion 9 in FIG. 1;

FIG. 10 is an enlarged view of the encircled portion 10 in FIG. 2;

FIG. 11 is another top rear perspective view of the beam projector showing a state of use with the main body rotated in relation to the base; and,

FIG. 12 is another bottom rear perspective view of the beam projector showing another state of use with the main body rotated in the opposite direction in relation to the base.

The broken lines in the figures depict portions of the beam projector which form no part of the claimed design.

The dot-dash broken lines in the drawing figures represent a boundary of the claimed design and form no part thereof.

The dot-dot-dash broken lines encircling portions of the claimed design that are illustrated in enlargements form no part of the claimed design.
